Attorney

UNITED STATES PATENT OFFICE.

CHARLES BLAKE, OF PONTIAC, ILLINOIS.

RAIL ANCHOR.

Application filed November 14, 1923. Serial No. 674,703.

To all whom it may concern:

Be it known that I, CHARLES BLAKE, a citizen of the United States, residing at Pontiac, in the county of Livingston and 5 State of Illinois, have invented new and useful Improvements in Rail Anchors, of which the following is a specification.

This invention relates to railroad equipment and more particularly to rail anchors.

10 The primary object of this invention resides in the provision of means whereby rattle and settling of the abutting ends of railroad rails will be eliminated.

Another object of this invention resides in 15 the provision of means whereby the abutting ends of the rails of railroads will be operably retained in alignment.

A still further object of this invention resides in the provision of a certain combination 20 of elements which, when assembled in operative position, will readily retain the abutting ends of the rails of railroads in operative alignment so they can easily be disassembled by an authorized individual.

25 A further object of this invention resides in the provision of means for securely anchoring the abutting ends of the rails of railroads so the natural shifting action thereof, due to climatic conditions, will not be affected.

With these and other objects in view, this invention resides in certain novel features of construction, arrangement and combination of elements to be hereinafter set forth in the 35 specification, illustrated in the accompanying drawings and pointed out in the appended claims.

In the accompanying drawings forming a part of this application:

40 Fig. 1 is a plan view of a portion of a railroad track showing the elements of this invention in operative engagement with the abutting ends of the rails thereof.

Fig. 2 is a side view thereof.

45 Fig. 3 is an enlarged cross sectional view on line 3—3 of Fig. 1.

Fig. 4 is an enlarged sectional view approximately on line 4—4 of Fig. 1.

50 Fig. 5 is a detail perspective view of one of the clamping plates.

Fig. 6 is a detail perspective view of one of the clamp bolts.

Fig. 7 is a similar view of one of the anchor rods.

55 In the present embodiment of this invention A designates concrete pillars having

laterally spaced pockets B formed in their upper surfaces for a purpose to be herein-after set forth.

Suitably embedded in the concrete pillars 60 A and extending above the bases of the spaced pockets B are anchor rods 5 which are provided with eyes 6 above the bases of the pockets.

Resting on the upper surface of each pillar 65 and covering the pockets therein is a bearing plate 7 having apertures 8 therein which are disposed in close proximity to the eyes 6 of the anchor rods 5 between the vertical planes occupied by the eyes 6 within each 70 pocket. The bearing plate 7 while adapted to cover the space pockets B are of such widths as to leave openings for inspecting the connections between the anchor rods 5 and clamping bolts to be hereinafter de- 75 scribed.

The letter R designates the abutting ends 80 of a pair of aligned rails which are adapted to rest on the bearing plate 7 of each pillar with their contacting ends disposed approximately midway between the vertical planes occupied by each set of anchor rods and are removably retained in rigid relation with the pillars through the instrumentality of apertured clamping plates 9 and clamping 85 bolts 10.

The clamping bolts 10 are provided with elongated bills 11 at their inner ends for engagement with the eyes 6 of the anchor rods and have their free ends threaded for the 90 accommodation of nuts 12 or the like, whereby the clamping plates 9 can be drawn downwardly against the flanges of the rails. Through the instrumentality of the elongated bills 11 of the clamping bolts 10, the 95 natural shifting action of the rails will not be affected during temperature variations and, should it become necessary to remove the rails, the nuts 12 can be loosened without trouble.

To further the alignment of the abutting ends of the rails any approved type of fish plates F may be utilized.

With this invention fully set forth, it is manifest that means have been provided to 105 not only secure the abutting ends of the rails of railroads in operable and noiseless condition, but provision has been made to reduce the cost of repairs and, through the simplicity of the embodiment of elements involved, the cost of installation will be insignificant.

Having thus described my invention, what I claim and desire to protect by Letters Patent is:

1. A rail anchor of the class described, comprising a pillar having pockets in its upper surface, anchor rods embedded in the pillar with their upper ends projecting into the pockets, clamping bolts loosely engaging the projecting ends of the anchor rods, an apertured base plate partially covering the pockets, clamping plates in spaced relation over the base plate and a nut on the free end of the clamping bolt.

2. A rail anchor of the class described, comprising a pillar having pockets in its upper surface, anchor rods embedded in the pillar with their upper ends projecting into the pockets, clamping bolts having elongated bills loosely engaging the projecting ends of the anchor rods, an apertured base plate partially covering the pockets, clamping plates in spaced relation over the base plate and a nut on the free end of the clamping bolt.

3. A rail anchor of the class described, comprising a pillar having spaced pockets in its upper surface, anchor rods embedded in the pillar with their upper ends projecting into the pockets, clamping bolts having elongated bills loosely engaging the projecting ends of the anchor rods, an apertured base plate partially covering the pockets, clamping plates in spaced relation over the base plate and a nut on the free end of the clamping bolt.

4. A rail anchor of the class described, comprising a pillar having pockets in its upper surface, anchor rods embedded in the pillar with their upper ends projecting into the pockets, apertured clamping bolts loosely engaging the projecting ends of the anchor rods, an apertured base plate partially covering the pockets, clamping plates in spaced relation over the base plate and a nut on the free end of the clamping bolt.

In testimony whereof I affix my signature.

CHARLES BLAKE.
